George W. Rogers,
INVENTOR

BY Victor J. Evans

ATTORNEY

WITNESS:

P. J. Hickey.

UNITED STATES PATENT OFFICE

GEORGE WALTER ROGERS, OF DUNDALK, MARYLAND

AVIATOR'S HELMET

Application filed July 21, 1928. Serial No. 294,362.

This invention relates to a helmet for aviators, the general object of the invention being to so form the helmet and its fastening means that the edges of the helmet will fit snugly against the forehead, the sides of the face and under the chin so that there is no danger of wind entering the helmet at the front thereof, which would not only be uncomfortable to the wearer, but would also cause flapping of portions of the helmet, thereby causing so much noise that the aviator could not hear any other noises.

Another object of the invention is to provide pads on the interior sides of the helmet for covering the ears of the user.

A further object of the invention is to provide means whereby the chin straps lie snugly together when in fastened position and without wrinkling or creasing.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:—

Figure 1 is a view showing the invention in use.

Figure 2 is a front view with the straps fastened together.

Figure 3 is a side view with parts broken away.

Figure 4 is a detail view showing how the straps are placed together when in fastened condition.

As shown in these views, I prefer to form the helmet of the two side sections 1 and the two central sections 2, these sections being suitably fastened together, such as by the double line of stitching 3. The front corners of the end sections are extended to form the straps 4, one strap being provided with a slot 5 through which the other strap is adapted to pass so that the straps will overlap each other and lie snugly together when in fastened posi-

tion. As will be seen, the straps are tapered toward their free ends so that the small end of one strap can be readily passed through the slot 5 in the other strap and without causing the straps to bulge as they would if the straps were not tapered. The straps are fastened by snap fasteners, a female part 6 of a fastener being placed at the free end of each strap and a plurality of male parts 7 are placed on each side section 1 at the front lower corner thereof to engage the female parts, thus enabling the helmet to be adjusted to suit persons of different sizes.

As shown in the drawing, the front part of the helmet is so formed that the upper part thereof extends well over the forehead of the wearer, with the front edges of the side sections 1 extending under the cheeks and with the straps passing under the chin, and it will also be seen that the parts are so formed that when the straps are fastened, the front edges of the helmet snugly fit the face so that wind cannot enter the helmet nor cause the side edges to flap, as it does when these side edges are not snugly held against the side portions of the face. It will also be seen that the manner of connecting the straps together, with one strap passing through a slot in the other, causes the straps to lie smoothly in overlapping relation and to snugly fit the chin.

Pads 8 are fastened to the inner faces of the side sections so as to cover the ears of the user and a short strap 9 is fastened to the rear of the helmet and has one end detachably connected with the helmet by the snap fastener 10 so that the strap of a pair of goggles can be placed under this strap and thus held to the helmet.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A helmet of the class described comprising a body part having its forward top edge ex-

tending to a point adjacent the eyes of the wearer and its side edges passing over the cheeks of the user and with its lower edge extending snugly around the neck of the user, said lower edge terminating in the lower edge
5 of the cheek engaging edges, a strap connected with each corner formed by the cheek and neck engaging edges of the helmet, said straps tapering to their free ends and one strap having a slot therein through which
10 the small end of the other strap passes, said slot being of greater length than the width of the strap, whereby the straps will snugly fit under the chin of the user and adjustable means for detachably connecting the free end of each strap to a part of the other strap comprising a separable fastener at the end of each strap.

In testimony whereof I affix my signature.
GEORGE WALTER ROGERS.
